NECKTIE

William S. Romme, Stamford, Conn.

Application December 9, 1943, Serial No. 513,542

5 Claims. (Cl. 2—155)

1

The present invention relates to improvements in neckties and more particularly to an improved tie which will not slip after being knotted and tightened.

Heretofore, it has been difficult to maintain a neat appearance after a tie has been knotted and adjusted because of the tendency of the knotted part to slip down out of place. This is especially true where the tie is made of slippery material, such as silk or rayon.

A previous attempt to solve this problem was made by providing a separate metal device having spurs which was slipped into the loop forming the knot to be attached to the fabric by the spurs after the knot had been almost completely made. This proved unsatisfactory for the sharp edges or spurs, by which the metal is attached to the fabric in the knot of the tie, would quickly tear and fray the material of the tie. Also, the metal device, being separate from the tie, was easily misplaced and lost.

An object of the present invention is to provide an inexpensive, easily manufactured tie having means incorporated therein which will prevent it from slipping, but which do not spoil the shape nor injure the fabric of the tie.

This has been accomplished in the form of the invention illustrated herein as exemplary thereof by making a tie having a series of protuberances or enlargements adapted to be trapped in the knot when the tie is tied and prevent the part about which the knot is formed from sliding up, i. e., lengthening the neck-encircling loop of the tie.

In the form of the invention herein illustrated, the protuberances or enlargements are in the form of buttons or disks. They are located on that portion of the inner lining which is within the standing portion of the tie and about which the knot is made, that is, the part which becomes the inside portion of the tie after it is knotted. The protuberances are, therefore, located within the knot after it is made and adjusted.

The protuberances are preferably located at the longitudinal edges of the lining, so that when the knot is made, their bulk or mass prevents them and the part of the tie at which they are located from passing inadvertently through the constricted opening in the upper corner of the knot.

The protuberance may be placed on only one longitudinal edge of the inner lining, but to insure against slipping they are preferably located on both longitudinal edges. When this is done,

the obstructions are preferably disposed alternately on opposite longitudinal edges.

The projections are covered by the folds of the tie which carry the inner lining and are therefore not visible, nor do they spoil the shape or detract from the appearance of the tie. They may be smooth surfaced and therefore the tie can be tied and untied in the ordinary manner without fraying or tearing the fabric.

10 It will be understood that, while it is preferable to have the obstructions remain on the tie when it is not being used to avoid the danger of misplacing or losing them, they can be removed and replaced whenever desired. When, as shown herein, the obstructions are formed by snap-fasteners between the parts of which the lining of the tie is caught, they may be easily removed to facilitate the laundering of the tie by simply separating the two parts of the fasteners.

Other features and advantages will hereinafter appear.

In the drawing—

Figure 1 is a front view of a necktie embodying the present invention.

25 Fig. 2 is a view of an untied necktie embodying the present invention showing the position of the protuberances in dotted lines.

Fig. 3 is a view taken along lines 3—3 of Fig. 2.

Fig. 4 is a view showing a portion of the lining 30 of the necktie, illustrated in Fig. 2.

In the form of the invention as illustrated herein, the necktie 10 may be made of any suitable necktie material. The necktie comprises a relatively narrow tab 11, a relatively wide tab 12, a neck band portion 13, and a lining 14 attached to and carried within the folds of the tabs and neckband.

To tie the necktie in the conventional manner, as shown in Fig. 1, the tie is placed on or under 40 the collar with the tabs 11 and 12 pendant. The tab 12 is then wrapped around the tab 11 to start the knot, and then the end of the tab 12 is inserted through and between the layers of the wrapped portion, thus forming a more or less 45 loose slip knot 15. After the knot has been pulled up on the standing part 11 to tighten the neck band portion about the collar of the wearer, the tab 12 is pulled to tighten the knot and constricts a passage 16 through which the standing 50 part of the tie extends. With the ordinary tie there is nothing but the friction between the parts and this is frequently insufficient to prevent the standing part 11 from sliding through the knot and thus causing a lengthening of the 55 neck encircling portion with the result that the

knot hangs loosely and does not stay up in position over the adjoining ends of the collar.

To prevent this slipping of the tie, after it has been knotted, the present invention in the form illustrated herein as exemplary thereof, provides a plurality of obstructing means 17 which are of such bulk or mass that they will not inadvertently pass through the knot, but will snag therein and anchor the standing portion 11 of the tie.

As shown, the obstructions 17 may comprise disks, buttons or the like, and these are preferably attached to the lining 14 of the tie 10. They may be attached either during the process of manufacturing the tie or after the tie is completely made, as preferred. As shown the obstructions are constituted by snap fasteners which may be fastened to the lining by simply pressing the separable parts 11a, 11b together while the lining is located between them.

The obstructions 17 are located on that portion 18 of the lining 14, which is carried by the part of the necktie consisting of the merging portions of the neckband 13 and standing part 11, that is, the part about which the knot 15 is tied.

Thus, when the knot is formed, the obstruction 17 will be located within the knot and after the tie is drawn into position by pulling on the standing part 11, the tab 12 is pulled to tighten the knot. This constricts the passage 16, and by so doing causes the obstruction 17 to be trapped within the knot, and this holds the knot from sliding down on the standing part 11. The obstruction 17 cannot escape from the knot without deliberately withdrawing the part 12 to open the passage 16.

In order that there will always be an obstruction located within the knot when the tie is tightened in place, regardless of variations due to the way various individuals tie their ties, or due to various neckband lengths, the present invention provides a plurality of such spaced obstructions.

In the form of the invention illustrated as at present preferred, the obstructions 17 are located alternately along both longitudinal edges 19 of the inner lining 14, that is, in zigzag fashion, but it will be understood that they may be placed in any desired way.

To unfasten the tie of the present invention, it

is merely necessary to grasp and pull up the part 12 at 20 where it extends into the knot and thereby enlarge passage 16 so that the obstruction 17 may freely pass therethrough. The untying and removal of the tie may then proceed as usual or desired.

Variations and modifications may be made within the scope of this invention and portions of the improvements may be used without others.

I claim:

1. A necktie having a standing part and a knot forming part and having disposed entirely within the standing part of the tie a protuberance adapted to be trapped in the knot formed in the tie to prevent slipping of the standing part back through the knot when the knot is tightened.

2. A necktie having a neckband portion and a knot forming portion, the adjoining parts of the neckband portion and the standing portion having a longitudinal series of protuberances disposed entirely within and enclosed by the tie, at least one of which becomes trapped in the knot to prevent slipping of the standing part back through the knot when the knot is tightened.

3. A necktie having a neckband portion, a standing portion, a knot forming portion and a lining, said lining having a longitudinal series of obstructions disposed within the tie, at least one of which becomes trapped in the knot when tied to prevent slipping after tightening thereof.

4. A necktie comprising a neckband portion, a standing portion, a knot forming portion and a lining; a longitudinal series of obstructions removably attached to said lining, said obstructions being attached on the part of said lining which is carried within the adjoining parts of the neckband portion and the standing portion of the necktie and becoming trapped in the knot when tied to prevent slipping of the standing part back through the knot when the knot is tightened.

5. As a new article of manufacture, a non-slipping necktie having a neckband, a standing portion, a knot forming portion and a lining, said lining having a plurality of obstructions, said obstructions being disposed alternately on opposite longitudinal edges of said lining and becoming trapped in the knot when tied to prevent slipping thereof when tightened.

WILLIAM S. ROMME.
